UNITED STATES PATENT OFFICE.

WILLIAM T. SMITH, OF BELLEFONTAINE, OHIO.

RAIL-JOINT.

1,192,698.

Specification of Letters Patent. Patented July 25, 1916.

Application filed May 14, 1915. Serial No. 28,144.

To all whom it may concern:

Be it known that I, WILLIAM T. SMITH, a citizen of the United States, residing at Bellefontaine, in the county of Logan and State of Ohio, have invented new and useful Improvements in Rail-Joints, of which the following is a specification.

The present invention relates to improvements in means for connecting the meeting ends of railway rails, the object being to simplify and improve the existing art by providing a chair upon which the meeting ends of the rails rest and connecting the angle bars or fish plates to the chair in such a manner as to prevent the downward movement of the rails at the joint thereof and also to obviate the liability of the creeping of the rails, but at the same time permitting of the necessary longitudinal movement thereof incident to the expansion and contraction of the rails.

With the above and other objects in view, the improvement resides in the construction, combination and arrangement of parts set forth in the following specification and falling within the scope of the appended claims.

In the drawings: Figure 1 is a perspective view of two rails connected in accordance with the present invention, Fig. 2 is a transverse sectional view approximately on the line 2—2 of Fig. 1, Fig. 3 is a similar sectional view approximately on the line 3—3 of Fig. 1, Fig. 4 is a perspective view of the rail chair, Fig. 5 is a similar view of one of the angle bars, Fig. 6 is a horizontal sectional view approximately on the line 6—6 of Fig. 2, Fig. 7 is a perspective view illustrating a slight modification, Fig. 8 is a sectional view approximately on the line 8—8 of Fig. 7, Fig. 9 is a detail perspective view of one of the sections of the chair, and Fig. 10 is a similar view of one of the spikes.

Referring now to the drawings in detail, the numerals 1—1 designate rails connected in accordance with the present invention, and 2—2 the ties upon which the rails rest. The rails are of the ordinary construction and in the preferred form of my device the ends of the rails are connected by angle bars 3—3, each of said angle bars having its vertical portion received within the fishing spaces of the rails and secured thereto through the medium of the usual connecting elements in the nature of bolts and nuts therefor. The horizontal flange of each of the angle bars is provided adjacent its

opposite ends, with outwardly extending tongues 4—4, the said tongues being preferably square or rectangular in plan.

The numeral 5 designates the chair member upon which the meeting ends of the rails are received. The chair includes a base 6 which is preferably horizontally straight and which also is preferably let into suitable openings in at least three of the ties. The chair is provided with vertically projecting longitudinally extending side flanges 7—7, each of said flanges embracing one of the opposite longitudinal edges of the connected rails, and the said side flanges are approximately centrally formed with extensions 8, the said extensions being provided with longitudinal slots 9 through which the tongues 4—4 of the angle bars pass. The chair 5 has its base to the opposite sides of its extensions 8 formed with flat horizontal projections 10, and, if desired, spikes may be inserted within the ties and engaged in notches in the said projections 10, and still further similar spikes may be forced into the ties to engage with the side flanges proper which are indicated by the numerals 7, the said spikes, of course, entering the ties 2.

In arranging the rails upon the chair one of the side plates or angle bars is first arranged upon the chair and has its tongues 4 passed through one of the side flanges of the chair. Next the rails are assembled upon the chair. Thereafter, the second angle bar is disposed at an angle to the rails, having its tongues passing through slots 9 upon the second extension of the side flanges. Thereafter, the said second mentioned angle bar is forced into contact with the rails and the nuts and bolts are adjusted as will readily be understood.

Upon the left hand side of the device illustrated in Fig. 1, I have shown fish plates or angle bars 11, the same having their vertical members received within the fishing spaces of the rails and the longitudinal edges of the horizontal flanges of said members 11 are bent below the rails and are received within suitable slots in one or more of the ties 1. These angle bars 11 are connected to the rails by the usual nuts and bolts, as clearly illustrated by the drawings.

In Figs. 7 to 9 I have illustrated a still further modified form of my device. In these figures the rails 12—12 are of the ordinary construction and the fish plates or angle bars 13—13 are also similar to those

previously described, the same being connected to the webs of the rails in the usual manner, such as by nuts and bolts and the said fish plates adjacent their opposite ends are formed with outwardly projecting tongues 14—14. The chair 16 is constructed of a pair of members each including a base which is approximately equal to one-half of the width of the rails and the inner or longitudinal edges of said chair members 16 are preferably bent downwardly or otherwise provided with longitudinally extending flanges 17. The ties 18 are recessed to receive the chair sections and each of said sections is provided with an outer longitudinally extending vertically disposed flange 19. Each of these flanges is approximately centrally provided with an upstanding portion 20 and each of the said upstanding portions is formed with a longitudinal slot 21 to receive the tongues 14—14 of the respective fish plates or angle bars 13—13. Extending longitudinally of the upstanding portions 20 and the base of each of the chair sections is formed an auxiliary extension 22 and each of said extensions is approximately centrally provided with a slot or opening 23, the said opening being preferably disposed approximately central of one of the ties 18, and passing through the opening 23 is the shank 24 of a securing member 25 which enters the central tie 18. This member 25 is provided with a right angular head 26 which engages with the vertical edge of the upstanding portions 20 of the chair members 16, and the said shank 24 is disposed between the tongues 14 which project a suitable distance beyond the members 20 of the chair sections 16. Of course, spikes 40 or other suitable securing elements may be inserted in the remaining ties, the said spikes having their heads contacting with the upper edges of the longitudinally extending flanges 17 and if necessary, with the outer longitudinal edges of the rails.

From the above description, taken in connection with the accompanying drawings, the simplicity of the device, as well as the advantages thereof will, it is thought, be perfectly apparent to those skilled in the art to which such invention appertains without further detailed description.

Having thus described the invention, what I claim is:

55 1. A joint member for rails comprising a chair having its base resting on three of the supporting ties and having vertical side flanges which are of a height approximately equal to the thickness of the edges of the flanges of the rails and which engage with

the said flanges, said sides at the portion thereof arranged over the central tie, being widened and formed with spaced longitudinal slots which have their lower walls disposed slightly below the tops of the flanges, 65 the chair below the widened portions of the side flanges having laterally extending horizontally disposed members which rest on the central tie, angle bars for the rails having the edges of their horizontal portions provided with extending tongues which are received in the mentioned slots in the side flanges of the base, and members having angular depending heads, said members being inserted through the horizontal extensions 70 of the chair and forced into the central tie, said members hugging the side and the widened portions thereof of the chair and having their heads engaging with the inner face of the said widened portions of the 80 sides and overlying the horizontal portions of the angle bars.

2. A joint member for rails including a chair having a flat base on which the rails rest, said chair being of a length to rest on three of the supporting ties and being formed with a central depending flange which is let into the ties, the base of the chair having vertical side flanges to contact with the edges of the rail flange and the said 90 side flanges at the portions thereof which overlie the central tie being widened vertically and being formed with longitudinal slots disposed approximately in a line with the edges of the flanges of the rails, the base 95 of the chair having outwardly extending flat portions at the center thereof and which are let into the mentioned central tie, angle bars of a length approximately equal that of the mentioned extension of the side flanges 100 of the chair arranged upon the opposite sides of the rails, the horizontal plate of each of the angle bars having outwardly projecting tongues which pass through the referred to slots in the central widened portion of the side flanges of the chair, and members having hook shaped heads passing through openings in the lateral extensions of the base of the chair and into the central tie, and the hook shaped head of each of the 110 said members embracing the central widened portion of the side flanges of the chair and overlying the horizontal plates of the angle bars.

In testimony whereof I affix my signature 115 in presence of two witnesses.

WILLIAM T. SMITH.
